US0D1017560S

(12) **United States Design Patent** (10) **Patent No.:** **US D1,017,560 S**
(45) **Date of Patent:** **** Mar. 12, 2024**

(54) **KEYPAD**

(71) Applicant: **Crestron Electronics, Inc.**, Rockleigh, NJ (US)

(72) Inventors: **Sae Jhun**, Bayside, NY (US); **Agnieszka Libson**, River Edge, NJ (US); **Benjamin Slivka**, Hillsdale, NJ (US); **Stan Wisniewski**, Pompton Plains, NJ (US)

(73) Assignee: **Crestron Electronics, Inc.**, Rockleigh, NJ (US)

(**) Term: **15 Years**

(21) Appl. No.: **29/852,778**

(22) Filed: **Sep. 9, 2022**

(51) LOC (14) Cl. **13-03**
(52) U.S. Cl. **D13/164; D13/174**

(58) **Field of Classification Search**
USPC **D13/162, 164, 171, 174**

Primary Examiner — Selina Sikder

(74) *Attorney, Agent, or Firm* — Crestron Electronics, Inc.

(57) **CLAIM**

The ornamental design for a keypad, as shown and described.

DESCRIPTION

FIG. 1 shows a top front perspective view of a keypad according to a first embodiment.

FIG. 2 shows a bottom front perspective view thereof.

FIG. 3 shows a front view thereof.

FIG. 4 shows a right side view thereof.

FIG. 5 shows a left side view thereof.

FIG. 6 shows a top view thereof.

FIG. 7 shows a bottom view thereof.

FIG. 8 shows a top front perspective view of a keypad according to a second embodiment.

FIG. 9 shows a bottom front perspective view thereof.

FIG. 10 shows a front view thereof.

FIG. 11 shows a right side view thereof.

FIG. 12 shows a left side view thereof.

FIG. 13 shows a top view thereof.

FIG. 14 shows a bottom view thereof.

FIG. 15 shows a top front perspective view of a keypad according to a third embodiment.

FIG. 16 shows a bottom front perspective view thereof.

FIG. 17 shows a front view thereof.

FIG. 18 shows a right side view thereof.

FIG. 19 shows a left side view thereof.

FIG. 20 shows a top view thereof.

FIG. 21 shows a bottom view thereof.

FIG. 22 shows a top front perspective view of a keypad according to a fourth embodiment.

FIG. 23 shows a bottom front perspective view thereof.

FIG. 24 shows a front view thereof.

FIG. 25 shows a right side view thereof.

FIG. 26 shows a left side view thereof.

FIG. 27 shows a top view thereof.

FIG. 28 shows a bottom view thereof.

FIG. 29 shows a top front perspective view of a keypad according to a fifth embodiment.

(Continued)

FIG. 30 shows a bottom front perspective view thereof.
 FIG. 31 shows a front view thereof.
 FIG. 32 shows a right side view thereof.
 FIG. 33 shows a left side view thereof.
 FIG. 34 shows a top view thereof; and,
 FIG. 35 shows a bottom view thereof.
 The broken lines in the figures depict portions of the keypad that form no part of the claimed design.
